(57) **CLAIM**

The ornamental design for a pedal board, as shown and described.

DESCRIPTION

FIG. 1 is a front perspective view of a pedal board according to our new design;

FIG. 2 is a front view of the pedal board of FIG. 1;

FIG. 3 is a right side view of the pedal board of FIG. 1, the left side view of the pedal board is a mirror image of the right side view;

FIG. 4 is a rear view of the pedal board of FIG. 1; and, FIG. 5 is a top view of the pedal board of FIG. 1.

Any features of the new design shown in broken lines are shown for illustrative purposes only and form no part of the claimed design.

1 Claim, 5 Drawing Sheets
